LUBRICATING APPARATUS

Alexander P. Fox, University City, and Victor G. Klein, St. Louis, Mo., assignors to Lincoln Engineering Company, St. Louis, Mo., a corporation of Missouri

Application August 30, 1937, Serial No. 161,638

2 Claims. (Cl. 285—161)

The present invention relates to certain new and useful improvements in lubricating apparatus, and it relates more particularly to lubricating apparatus of the general character disclosed in United States Letters Patent Nos. 1,959,517; 1,959,529; 1,947,208; and 2,010,174, wherein a temporary, fluid-tight connection is made between a grease-cup or so-called lubricant-receiving "fitting" or lubricant-receiving "nipple," on one hand, and a lubricant dispensing pump, compressor, or so-called "grease-gun," on the other hand, through a lubricant-delivery nozzle or a coupler which is held against the grease-cup by manual pressure applied by the operator during the actual delivery of the grease from the pump to the grease-cup.

Grease-delivery or lubricant-delivery couplers or nozzles of this general type shown in Patents Nos. 1,959,517; 1,959,529; 1,947,208; and 2,010,174, may be generally referred to as "push-contact" nozzles insofar as sealing contact or operative contact between the grease-cup and the grease-delivery coupler or nozzle of the "grease-gun" is maintained by merely manually pushing the nozzle against the grease-cup during grease-injection or grease-delivery.

Push-contact type grease-delivery or lubricant-delivery couplers or nozzles may be generally classified or divided into two groups, according to whether the nozzle makes contact with the grease-cup or lubricant-receiving "fitting" or "nipple" on the outside of the latter, or whether it makes contact with the lubricant-receiving "fitting" or "nipple" on some inner surface thereof, as for instance, along the internal edge of the lubricant-receiving hole or aperture of the grease-cup, "fitting" or "nipple".

The "externally-contacting" type of push-contact couplers or nozzles may be exemplified by the lubricant-delivery nozzles shown in United States Patents Nos. 1,459,662; 1,736,160, 1,494,652; and by the structure shown in Figures 1, 2 and 3 of Patent No. 1,475,980; and by the structure shown in Figures 1 and 2 of Patent No. 1,551,261, (and many others), while the "internally-contacting" type of push-contact couplers or nozzles may be exemplified by the lubricant-delivery nozzles shown in United States Patents Nos. 1,582,969; 1,673,459; 1,684,946; 1,716,501; 1,793,492; 1,840,111; and by the structure shown in Figures 4, 5 and 6 of Patent No. 1,475,980; and by the structure shown in Figure 3 of Patent No. 1,551,261; and British Patent No. 140,355 (of 1920).

Owing to the fact that the lubricant-receiving

apertures or holes in push-contact type grease-cups, "fittings" or "nipples" are preferably made as small as may be permitted by allowable manufacturing costs (so as to minimize the amount of dirt which may get into the grease-cup through the inlet aperture which is normally exposed), push-contact type lubricant-delivery nozzles of the internally-contacting kind must be correspondingly small; and because of their small size raise the problem of conveniently guiding the tip of the nozzle into alignment with the hole in the grease-cup or lubricant-receiving "fitting" or "nipple."

Each of the "internally-contacting" push-contact nozzles shown in Patents Nos. 1,959,529; 1,947,208; and 2,010,174, has added means for guiding the small grease-delivery tip of the "internally-contacting" push-contact nozzle into alignment with the hole of the grease-cup or lubricant-receiving "nipple."

One of the problems in providing such guiding means for nozzles of this general character is to permit the operative meeting of nozzle-tip and a grease-cup hole even though they are not in true axial alignment, but have their axes at a slight angle to each other within a reasonable range of "angularity."

A further problem in providing such guiding means for nozzles of this general character is to permit a suitable axial inclination or suitable "angularity" between nozzle and grease-cup without strain on the small or fine lubricant-delivery tip of the nozzle while the nozzle and grease-cup are in operative contact with each other and while grease is being delivered.

Thus, to get a reasonably dependable and durable guiding effect, a substantial amount of telescoping of nozzle-guide over grease-cup is desirable, as in Patent No. 1,959,529, but such substantial telescoping of nozzle-guide over the grease-cup body involves either a substantial clearance between the so telescoped portions, in which event the guidance is not as accurate as may be desired for the very fine lubricant-delivery tip and lubricant-receiving hole, or if the clearance is reduced, the "angularity" both in approach or operative meeting as well as after contact is established, is curtailed to some extent.

By means of the inwardly extending guiding flange 19 of Patent No. 2,010,174, which may fit over the head of the grease-cup of said Patent No. 2,010,174, and the groove 63 in said grease-cup beneath the head, not only is close or accurate guidance between grease-cup and nozzle obtainable, but a substantial amount of "angularity" is

obtainable between nozzle and grease-cup (while grease is being forced into the grease-cup) without "prying" the fine tip of the nozzle away from the lubricant-receiving hole of the grease-cup.

5 The guide construction shown in Figure 1 of Patent No. 2,010,174 requires, however, that the grease-cup or lubricant-receiving nipple be provided with a peripheral clearance groove.

One of the objects of the present invention 10 is to provide an internally-contacting push-contact coupling which may be interchangeably and equally effectively used on the various different kinds of "push-contact" type of grease-cups, that is, those having the downwardly and out- 15 wardly flaring side-wall as shown in Patent No. 1,947,208; those having a generally cylindrical side-wall devoid of any peripheral clearance groove, of the kind shown generally in Patent No. 1,959,529, and those having a clearance groove or reduced neck portion, as for instance, 20 that shown in Patent No. 2,010,174.

A further object of the present invention 25 is to provide such interchangeable or universal type of internally-contacting push-contact coupling, which may telescope over the grease-cup or lubricant-receiving "fitting" or "nipple" to a substantial extent, and with a close enough clearance between telescoping surfaces to assure accurate meeting of lubricant-delivery tip 30 and lubricant-receiving hole, and which will yet permit of a substantial "angularity" both in "approach" as well as during lubricant-delivery without prying the lubricant-delivery tip of the nozzle from the lubricant-receiving hole of the 35 grease-cup.

With the above and other objects in view which will appear more fully from the following 40 detailed description, the present invention comprises, among other things, the elements and combinations of elements, features of construction, and arrangement of parts, which will be exemplified in the structures hereinafter described, and the scope of the application all of which will be indicated in the following claims.

45 In the accompanying drawing, in which like reference characters indicate like parts,

Figure 1 represents a longitudinal sectional view (on a much enlarged scale) of the lubricant-delivery device or coupler and grease-cup 50 embodying the present invention, with the nozzle and grease cup shown in axial alignment with each other.

Figure 2 represents a sectional view similar to that shown in Figure 1, but with the axes of 55 the nozzle and grease-cup at a slight angle to each other.

Figure 3 represents an enlarged view of the so-called needle forming part of the nozzle construction.

60 The coupler may include a tubular body portion 1, which may be threaded at its rear end either externally or internally, as at 2, whereby it may be affixed to the discharge opening of a lubricant dispensing pump, compressor or 65 "grease-gun" in the general manner shown in Patents Nos. 1,971,778 and 2,038,761, or to the delivery-end of a lubricant discharge pipe or conduit or valved handle of a lubricant dispensing pump, compressor or "grease-gun," as for instance, the valved lubricant dispensing handles 70 shown in Patents Nos. 1,733,441 and 1,812,798, and shown in Figures 1 and 2 of Patent No. 1,925,532 and shown in Figures 1 and 7 of Patent No. 1,963,783 and in Figures 6, 7 and 9 of Patent 75 No. 1,654,673, or the tubular body portion 1 may

be formed integrally with or in continuation of the high-pressure cylinder of the grease-gun, as in Patent No. 2,010,174, for instance.

The body 1 is preferably provided with a small-diameter opening 3, followed toward its outer 5 end by a larger diameter opening 4, whereby an annular transverse shoulder 5 is provided, against which is closely fitting gasket 6 is adapted to rest;—the gasket 6 being of a suitable lubricant-resistant and yet more or less resilient 10 material, and preferably fitting snugly within the larger bore 4 of the tubular body portion 1 of the nozzle.

The gasket 6 may be any of the so-called artificial rubber compositions, some of which are 15 known in the trade as "Duprene," "Neoprene," "Thikol," etc.

The nozzle proper designated generally by the numeral 7 consists of a generally tubular shank portion 8, which projects and extends into the 20 central hole or aperture in the gasket 6, the flange portion 9 which extends laterally and bears against one flat face of the gasket 6, and the tip portion 10 which is also tubular and the outer surface of which is generated by the rotation of an arc of a circle about the axis of the nozzle 7;—the center of the arc of the circle being outside the solid generated by such rotation of the circular arc, as shown particularly in Figure 3. As the taper at any point along the 30 tip 10 is determined by the inclination of a tangent to such circular arc, such taper, instead of being uniform, is gradually varying from the end of the tip backwardly along the tip. Thus, the taper becomes more and more gradual, or 35 becomes less and less, as the so generated surface recedes from the end of the tip. As the diameter of the hole 11 of the grease cup or so-called lubricant-receiving "fitting" or "nipple" 12 may vary, in diameter, and indeed may be enlarged 40 after the grease-cup has been used for some time, the nozzle tip 10 may enter deeper and deeper into the grease-cup; and as its entry into the grease-cup increases the taper at the circular zone of contact decreases.

An outer sleeve-like shell 13 is threadedly superimposed or mounted upon the end of the tubular body member 1, by means of the screw thread 14, and serves, among other things, to clamp a metallic washer or disc 15 rigidly in 50 place to act as a separator for supporting the nozzle 7 on one hand, and the guide-cup 16 on the other hand;—the disc 15 being held in place between the transverse terminal surface 17 of the tubular coupler body 1 and the slight 55 transverse shoulder 18 formed in the shell 13.

The disc 15 is provided with a central aperture 19 through which the tip portion 10 of the nozzle 7 projects. The parts are so proportioned that when the disc 15 is clamped firmly in place, the flange 9 of the needle nozzle 7 is pressed tightly 60 against the flat transverse face of the gasket 6 so as to form a fluid-tight seal.

At the outer end of the tubular sleeve 13, an in-turned annular flange 20 is provided whose 65 inner periphery is of a diameter substantially greater than the diameter of the head 21 of the grease-cup 12 in relation to which the nozzle is to be guided, and indeed is of a diameter so great in relation to the head of the grease-cup 70 that the in-turned flange 20 could not, in and of itself, provide adequate guidance for the tip 10 of the nozzle 7.

The in-turned flange 20 is provided with an inclined internal surface 22 which may be either 75

uniformly tapered, as indicated, or which may be of a curved contour as for instance, an annular portion of a sphere or an annular portion of some other curved body, thereby to provide a "rocking" seat for the curved end-surface 23 of the guide-cup 16. The guide-cup 16 may be provided with a generally cylindrical inner surface 24 of a diameter just sufficiently greater than the diameter of the head 21 of the grease-cup so as to telescope over it with a neat fit (a few thousandths of an inch being allowed for variations in head-diameters of grease-cups resulting from mass production of the grease-cups). The guide-cup is also provided with a smaller diameter rear opening or aperture 25 through which the tip portion 10 of the nozzle 7 extends and which is sufficiently large to give wide clearance around the nozzle tip 10. The rear external surface 26 of the guide-cup 16 is again of curved contour so as to permit the rocking of the cup in the manner indicated in Figure 2. A helical compression spring 27 is interposed between the disc 15 and the transverse annular surface or shoulder 28 near the outer end of the cup 16, which serves to press the cup 16 against the annular internal inclined surface 22 of the in-turned flange portion 20 of the sleeve 13.

Whenever the nozzle approaches the head of the grease-cup at a slight angle, as indicated in Figure 2, the guide-cup 16 is cocked to one side as indicated in Figure 2 and serves as centering means to guide the tip 10 of the nozzle 7 into the hole 11 of the grease-cup 12.

The parts are so proportioned that the contact zone on the tip 10 will be more or less approximately in the center of the rocking motion of the cup 16 so that however the cup 16 may rock at a slight angle, the principal zone of contact on the tip 10 will be at or near the center of such rocking motion so that the hole in the head of the grease-cup will nevertheless be guided to the tip 10.

Likewise, if the grease-cup and nozzle are brought into contact with each other in axial alignment as indicated in Figure 1 and thereafter, and during the course of the greasing operation, the nozzle should be inclined slightly as in Figure 2, such slight inclination may be effected without any tendency to pry the tip 10 from the hole 11 because the guiding surface 24 which has theretofore been telescoped over the grease-cup is not stationary or rigid in relation to the nozzle but is movable so that it can adjust itself without any pressure on the side of the grease-cup.

The word "surface" as used in the claims comprehends both relatively substantial surfaces, as for instance the surfaces 22 or 23 illustrated in Fig. 2, and also surfaces of generally limited extent, as for instance the narrow surfaces provided by corners or the like, such as the limited surface provided by the lowermost edge of surface 22.

The present invention may be embodied in other specific forms without departing from the spirit or essential attributes thereof, and it is therefore desired that the present embodiment be considered in all respects as illustrative and not restrictive, reference being had to the appended claims rather than to the foregoing description to indicate the scope of the invention.

Having thus described the invention, what is hereby claimed as new and desired to be secured by Letters Patent is:

1. In a lubricant coupling device for connecting a lubricant supply conduit with an end-aper-tured grease-cup and including a tubular coupling-body having mounted within it a tubular needle-type lubricant-delivery nozzle generally stationary with respect to said coupling, a spring-pressed guide member surrounding the tip of said needle-type nozzle and angularly movable with respect thereto and having a substantially convexly spherical end surface, and means providing a cooperating seat for rockingly receiving said end surface, said latter means being fixedly related to said coupling.

2. In a lubricant coupling device for connecting a lubricant supply conduit with an apertured grease-cup, said device including a tubular coupling body having mounted within it a tubular needle-type lubricant-delivery nozzle generally stationary with respect to said coupling, angularly movable means for guiding the tip of said needle-type nozzle into sealing contact with the edge of the aperture of said grease-cup comprising a generally tubular guide member surrounding the tip of said needle-type nozzle and angularly movable with respect thereto, a guide-retaining sleeve fixedly related to said coupling and having a seating surface for rockingly receiving said angularly movable guide member, and spring means urging said angularly movable guide member up against said seating surface;—the center of movement of said angularly movable guide member being generally in the zone of contact between said needle-type nozzle and said grease-cup.

ALEXANDER P. FOX.
VICTOR G. KLEIN.
